UNITED STATES PATENT OFFICE.

CHARLES WILLIAM PHIPPS AND WILLIAM JOHN STEELE, OF NORTHAMPTON, ENGLAND;
SAID STEELE ASSIGNOR TO SAID PHIPPS.

CEMENTING APPARATUS.

No. 885,862.

Specification of Letters Patent. Patented April 28, 1908.

Application filed January 4, 1907. Serial No. 350,749.

To all whom it may concern:

Be it known that we, CHARLES WILLIAM PHIPPS, trading as PHIPPS & SON, merchants and manufacturers, and WILLIAM JOHN STEELE, engineer, both subjects of the King of Great Britain, citizens of Northampton, England, residing at Guildhall Road, Northampton, England, have invented new and useful Improvements in Cementing Apparatus, of which the following is a specification.

This invention relates to apparatus for containing cement, adhesive or the like and is particularly, though not exclusively, applicable to the type of cementing machine employed in coating with cement the edges of material, such for example as sections of the uppers of boots and shoes to unite them temporarily preparatory to their being permanently connected together in a sewing machine. Machines of this character have heretofore comprised in their construction a vessel or receptacle to contain the main supply or stock of cement, a closable opening through which the vessel is filled, a trough having a duct communicating with the main receptacle and for containing a small quantity of the cement for immediate use and a shutter to close the trough or its duct so that the cement, which may be of a highly inflammable nature, may not remain exposed when not in actual use.

The present invention relates to an improved construction of machine comprising a main vessel or stock receptacle, a feed opening or inlet therein, a slidable door thereto having a locking device, such for example as a spring controlled pin or bolt and lever, to lock the said door in its closed position and secure the cement against exposure to the atmosphere, and means, such for example as a cam lever, to withdraw or slide the door or lid away from the feed inlet of the vessel or cement pot.

The invention also comprises a valve which automatically closes and opens the duct leading from the receptacle to the trough synchronously with the opening and closing respectively of the feed opening. While the valve and duct are open the cement will be maintained at a uniform height in the trough, but when the sliding door of the feed opening is withdrawn it is advisable to close the said duct to prevent a rush of cement into the trough and an overflow of the latter. When however it is only desired to

replenish the trough by allowing cement to flow through the duct into the latter, or to cut off the communication between the trough and the main supply in the receptacle, the locking device of the sliding door is not released, and the cam lever is given a sufficient amount of movement to operate the valve rod and valve to open or close the said duct. The cement may be taken from this trough by a brush and the operator may paint or coat the edges of the upper sections with it in the well understood manner. In order however to effect this operation *i. e.* coating the edge of the upper section, mechanically and automatically, as far as we are aware for the first time, a roller may be revolubly located and dip in this trough so that when the edge of the upper section is passed thereover it will take up the cement from the surface of the roller and become coated thereby and at the same time will by frictional contact simultaneously rotate the roller in the trough so as to bring a fresh surface of the roller to the next upper section.

A pressure device preferably in the form of a roller may be employed to press the upper section on to the coating roller. Such pressure roller is normally held out of contact with the coating roller by a spring or equivalent means so as to keep it clean and prevent it coating the opposite edge of the upper section as it would do if both rollers were in surface contact. The coating roller may also if desired be positively driven through the medium of suitable mechanism such for example as gear wheels, a driving shaft and belt pulley thereon.

When it is desired to coat both sides or edges of the upper section or other fabric with cement the pressure roller and the coating roller are allowed to be permanently in surface contact.

The invention will be further described in detail and reference made to the accompanying drawings wherein:

Figure 1 is a front elevation of a cementing apparatus constructed in accordance with this invention. Fig. 2 is a longitudinal section of the apparatus and Fig. 3 is a plan of same. Figs. 4 and 5 are plans of the main parts of the apparatus and show the slidable door in its closed and open positions respectively.

Like reference characters are employed to designate the same parts in all the figures.

In a machine constructed according to the present invention 1 represents a main vessel or stock receptacle furnished at its upper end with a slidable lid or door 2 having a locking device to lock it in its closed position. A convenient construction of locking device comprises a spring controlled bolt 3 carried in a fixed bracket 4 and operated vertically therein to unlock the lid by depressing one end of a lever 5 pivoted to said bracket as shown in Figs. 2 and 3. The stock vessel 1 has a feed inlet or filling opening 6 therein and when the latter is covered and closed by the slidable door 2, as shown in Figs. 1 to 4, the locking bolt 3 under the influence of its spring bears with pressure upon and forces the said door 2 down air-tightly upon a joint ring 7 of rubber or equivalent material arranged around the feed inlet and thus secures the cement against exposure to the atmosphere.

The slidable door or lid 2 may be withdrawn from over the feed opening 6 of the stock vessel for filling purposes by means of a cam lever 8 the latter (after the bolt 3 is lifted from the door 2 by depressing the free end of the lever 5), slides the said door to the withdrawn position shown in Fig. 5.

The front lower portion of the stock receptacle 1 is furnished with a trough 9 and a duct 10 communicates between the said trough and the interior of the stock receptacle, to permit cement to flow into the trough. A convenient construction of valve for controlling the flow of the cement through the said duct 10 to the trough comprises a vertical rod 11 located within, and extending the full length of the stock vessel, as shown in Fig. 2, the upper end of said rod being connected to the cam lever 8 and is operated thereby. The lower end of the rod 11 is provided with a diametrical hole forming a valve 12 so arranged that it may be moved into alignment or register with the duct 10 and thereby form a through passage for the cement to flow into the trough from the stock vessel, as shown in Figs. 2 and 3; upon the said rod being partly rotated it will close the said duct 10 by bringing a solid or unperforated portion of the rod 11 opposite thereto as shown in Figs. 4 and 5, and thus stop the cement feeding to the trough.

The cam lever 8 is attached to the valve rod 11 in such a position that when the said lever is moved to withdraw the door and uncover the feed opening 6 the rod will be synchronously turned thereby to the position to close the duct 10, as shown in Fig. 5, and vice versa. This simultaneous action of opening the door and closing the duct will only be necessary when it is desired to re-fill the stock receptacle. When however it is required to open the valve to replenish the trough 9 only, by allowing cement to flow thereinto through the duct 10, or to cut off

the communication between the said trough and the stock receptacle, the locking bolt 3 is not lifted or released as the cam slot 13 of the cam lever 8 is of such a length as to permit the requisite amount of movement of 70 said lever over and past the locked lid 2 to rotate the valve rod 11 and open or close the duct 10 as shown in Figs. 3 and 4 respectively.

The movement of the lever 8 to open the feed inlet 6 of the main vessel is limited by a 75 stop pin 14, Figs. 3 to 5, and it will be noticed, by reference to the last named figure, that owing to the particular positions of the lever 8 and valve or hole 12 on and in the rod 11 it is impossible to open the feed inlet 6 and 80 door 2 without first closing the duct 10. For the purpose of mechanically and automatically coating the edge of a boot upper section or similar goods the machine is furnished with a roller 15 revolvably located in the 85 trough 9 so that its lower part constantly dips in the cement. When the said roller is rotated by the passing thereover of an upper section or by positive driving means, as hereinafter described, it will take up the cement 90 and thereby coat the goods placed in contact therewith.

A pressure roller 16 is carried on a pivoted lever 17 Fig. 1 the said roller being normally held out of contact with the coating roller 15 95 by a spring 18 Figs. 1 & 3.

The pivoted lever 17 of the pressure roller 16 is connected by means of a chain 19 to a foot pedal or knee lever (not shown) so that when either of the latter is actuated it will 100 lower the pressure roller 16 on to the upper section or other work and press it into positive contact with the coating roller, to receive a coating of cement therefrom. The surface of the latter roller may be milled or serrated 105 and the lowering of the pressure roller 16 by the operator's foot or knee leaves both his hands free to manipulate the work passing between the rollers.

Mechanism may be arranged to positively 110 drive or revolve the coating roller 15 and this mechanism according to one arrangement may consist of a driving shaft 20 actuated by bevel wheels 21 from a belt pulley 22 the said roller being driven from the shaft 20 by intermediate gear wheels 23 Figs. 1 and 2.

When it is desired to coat each of the two opposite sides or edges of the upper section or other fabric with cement the pressure roller 16 and coating roller 15 are allowed to 120 be permanently in surface contact so that the cement will be taken up by the coating roller and transferred thereby to the top or pressure roller.

When no coating or pressure rollers are 125 employed the operator removes the cement from the trough by a brush and applies it to the material in the well known manner. When however the coating roller or rollers is or are employed the cement is allowed to 130

flow continuously through the duct 10 into the trough while the machine is in use. The most important feature however of the invention is the arrangement by which the 5 valve which controls the supply of cement to the trough, and the opening and closing of the door over the feed inlet are controlled by the same lever 8 the latter being so arranged that when moved in one direction (shown by 10 the arrow) to the limit of the cam slot it rotates the rod 11 and removes the hole 12 therein away from and out of register with said duct so that the valve and duct are closed and the flow of cement to the trough 15 is stopped. The lever, if its movement is continued will by pressing against the pin on the door 2 slide the latter along and withdraw it from over the feed opening 6 to permit of the stock vessel being re-filled. It 20 will be obvious therefore from the foregoing description, that the movement of the lever 8 within the limit of the slot in one direction will open the valve and duct so that cement may flow into and replenish the trough and 25 the movement of the said lever within the limit of the slot in the opposite direction will close the valve and duct and cut off the supply of cement to the trough.

If the movement of the lever is continued 30 in the first named direction after the valve and duct are opened the lever closes the door upon and over the feed inlet and if the movement of the lever is continued in the opposite direction (shown by the arrow) after the valve 35 and duct are closed the lever slides the door away from and exposes the feed inlet. The said lever therefore with a limited movement in opposite directions opens and closes respectively the valve and duct and with a further and continued movement in the same 40 directions closes the said valve and duct and opens the door or opens the said valve and duct and closes the said door.

What we claim then is:—

45 1. A cementing machine, comprising a stock receptacle, a trough communicating therewith, a feed opening in the said receptacle, a door and means to slide the said door over and away from the said opening respectively, a spring controlled bolt to lock the said door in its closed position and a lever to release the said bolt and unlock the door.

50 2. A cementing machine, comprising a

stock receptacle, a trough communicating therewith, a feed opening to the said receptacle, a door, and a cam lever to actuate the said door to close and open respectively the said feed opening. 55

3. A cementing machine comprising a stock receptacle, a trough, a duct communicating therebetween, a valve rod extending from top to bottom and inside of the stock receptacle and having in its lower end a through opening which upon the said rod being rotated is moved either into or out of register with the said duct to permit or check the flow of cement into the said trough, and means located exterior to and at the top of the stock receptacle and connected to the said rod to rotate the latter for the purpose 70 described.

4. A cementing machine, comprising a stock receptacle, a trough, a duct communicating therebetween, a valve to open and close the said duct, a rod connected to said valve, 75 a feed opening to said receptacle, a door to said opening and a lever to simultaneously slide the said door away from said opening and actuate the said rod to close the said valve for the purpose described. 80

5. A cementing machine comprising a stock receptacle, a trough, a duct communicating therebetween, a valve to open and close said duct, a rod connected to said valve, 85 a feed opening to the said receptacle, a door to said opening and a lever to simultaneously slide the said door to close said feed opening and actuate the said rod to open the said valve for the purpose described.

6. A cementing machine comprising a 90 stock receptacle, a trough, a duct communicating therebetween, a valve to open and close the said duct, a feed opening to said receptacle, a door to the said opening, a lever to simultaneously actuate said door and 95 valve, a coating roller located in said trough and mechanism to positively revolve said coating roller for the purpose described.

In testimony whereof we have signed our names to this specification in the presence of 100 two subscribing witnesses.
